UNITED STATES PATENT OFFICE

JOSEPH M. GAAR AND JOHN C. F. LASER, OF INDIANAPOLIS, INDIANA.

WATER-COOLER.

No. 830,219.

Specification of Letters Patent.

Patented Sept. 4, 1906.

Application filed December 2, 1904. Serial No. 235,273.

To all whom it may concern:

Be it known that we, JOSEPH M. GAAR and JOHN C. F. LASER, citizens of the United States, residing at Indianapolis, in the county 5 of Marion and State of Indiana, have invented certain new and useful Improvements in Water-Coolers, of which the following is a specification.

This invention relates to improvements in 10 apparatus for cooling water, and is here shown as applied to means for cooling the water used for supplying the water-jacket surrounding the parts of an explosive-engine that become commonly heated during the 15 operations of such engines and in the drawings is shown as used for cooling the gasolene-engine of an automobile, but it is not desired to limit it to automobile construction nor to engine construction. It is desired to 20 include all uses to which the invention is applicable.

The object of the invention is to conduct the heated water through conduits which will have the largest obtainable surface exposed to the air for the purpose of cooling the 25 water contained within said conduits.

A further object of the invention is to provide a simple, compact, durable, and inexpensive apparatus and one that will be easy 30 to operate and to keep in repair.

We accomplish the objects of our invention by the mechanism illustrated in the accompanying drawings, in which—

Figure 1 is a perspective view of an automobile, provided with our improved water-cooling apparatus. Fig. 2 is a front elevation of said apparatus. Fig. 3 is a longitudinal vertical section of same. Fig. 4 is a side elevation of our invention, showing the upper end in cross-section. Fig. 5 is a plan view showing some of the parts broken away to illustrate the underlying construction. Fig. 6 is a detail in plan view of the device with the cap removed and showing the top 45 horizontal plate broken away in part. Fig. 7 is a detail in vertical section of an upper corner of the cooler. Fig. 8 is a detail showing one of the cooling-pipes which is broken away in part, and Fig. 9 is a detail in perspective, showing the middle body portion of the cooler broken away in part and showing the cap and base sections as dismembered to better illustrate the manner in which they are joined together. Fig. 10 is a 50 detail in vertical section of the lower chamber of the cooler, showing a modified form of

air-tube passing therethrough, the walls of which are funnel-shaped. Fig. 11 is a detail showing one of the cooling-pipes on a larger scale than the other figures of the drawings, 60 the view being in vertical section on the line 11 11 of Fig. 12, and Fig. 12 is a vertical section on the line 12 12 of Fig. 11.

Like characters of reference indicate like parts throughout the several views of the 65 drawings.

Referring to the drawings, 10 is the base of our cooling apparatus, and is here shown as a rectangular sheet-metal box, with a sheet-metal cover 14, preferably of copper. This 70 box is divided into two compartments 11 and 12 by means of the partition 13, which prevents direct communication between said compartments. As shown in Fig. 5, the sheet-metal cover 14 is provided with a 75 large number of perforations 16, each of which are long and narrow, as shown, and are arranged in a series of staggered rows. A tube 17, one for each opening, is secured in said perforations in a manner to provide a 80 water-tight joint with plate 14. These tubes 17 are flattened, as shown in Fig. 6, so that the opening through them presents a long and narrow space for purposes which will be hereinafter explained. The plate 14, 85 which forms the cover to the above-described box, also forms the bottom of the central or main portion of the water-cooler, being that portion in which the tubes 17 are located. This portion includes the side plates 18, 90 which support the top metal frame 19 and form, with their related parts, a casing for the tubes 17, which is open at both front and rear. Between the bottom box and its cover 14 is a second frame 19, which gives strength 95 and rigidity to the construction. This frame 19 has the dowel-pins 20, which pins are provided with transverse slots in alignment for the several pins to receive a key, which will be driven therein after the parts 100 are assembled for the purpose of locking together and securing said parts.

Supported upon the top frame 19 is the cap 23, which has a top, as shown as curved in the drawings, but which may be of any desired shape and is closed at front and back to form a water-tight hollow structure. This cap will have dowel-pins 25, similar to the dowel-pins 20 previously described, which are slotted in the same manner and for the same purpose. 27 is a metal plate, preferably of copper, which is laid between the cap

23 and top frame 19, so as to form a gasket to make a tight joint between the parts. The flattened tubes 17 will pass through this plate 27 and will make a water-tight joint therewith. The open ends of tubes 17 will communicate at their tops with the interior of the hollow cap 23, and at their lower ends the said tubes will be in open communication with the compartments in the bottom box. 5 The cap 23 will have the opening 30 at its top for the purpose of filling the cooler with water. This opening will be provided with a suitable removable closure. The cap 23 will have the transverse partition 31, dividing its interior into two separate compartments. Extending longitudinally through both compartments of cap 23 is the pipe 33, which is perforated at frequent intervals throughout its length, and connecting with said pipe 33 10 is the pipe 37, which is connected with the water-jacket of a gasoline-engine or any other supply from which water is obtained in a heated condition and which is to be cooled. This water entering through pipe 37 is discharged through the perforations in pipe 33 15 into the hollow interior of cap 23 and is carried through tubes 17 down into the compartments 11 and 12 in the box at the base. 20 39 is a pipe which takes from compartment 12 and discharges the cooled water back into the water-jacket of the engine or whatever is to be supplied. The purpose of the partitions 13 and 31 is to divide their respective vessels into compartments, which will prevent the flow of the water longitudinally of 25 said vessels, thereby compelling it to pass back and forth on a longer travel through the series of cooling-tubes 17. Thus water supplied through tube 37 will pass down into compartment 11 through those tubes 17 that have their inlets between the partition 31 and adjacent end of the cap 23, and the water from compartment 11 will pass up to the cap on the other side of partition 31 through 30 those tubes 17 that have their inlets between the mouths of the first set and a partition 13, and the water thus delivered to the cap 23 through said tubes 17 is carried down again from the cap into the compartment 12, 35 through the tubes 17, that have their discharge-openings into said compartment 12, and from the latter compartment the water which has been thus subjected to the cooling action of the air bathing the outside of the tubes 17 is carried off for use through pipe 39. By flattening the tubes, as shown and 40 previously described, a very thin column of water is carried through them, and this column is exposed to the largest possible cooling 45 action of the air passing or surrounding said tube. In order to retard the flow of the water through tubes 17, their discharge ends may be contracted by pressing their walls closer together, as shown in Fig. 8. 50 60 65 42 are a series of pipes extending trans-

versely through the cap 23 and the compartments 11 and 12 of the base. These pipes are open to atmosphere at both ends and provide air-conduits through their respective chambers for the cooling of the water contained in said chambers by the flow of air through said pipes 42. 70

47 represents a tubular opening through the base for the insertion of the starting-crank of an automobile and has nothing 75 whatever to do with the operation of our cooler proper.

Our invention is capable of various modifications and variations in construction without departing from the spirit of the invention, 80 and we do not therefore desire to limit ourselves to the exact construction shown, nor do we desire to be understood as limiting our invention to automobiles or to the cooling of explosive-engines; but 85

What we do claim as new, and wish to secure by Letters Patent of the United States, is—

1. In a cooling apparatus, two or more chambers, and a plurality of tubes forming 90 communications between said chambers, said tubes being contracted in one diameter to form passages of greater length in cross-section than width and said tubes being additionally contracted on the same diameters 95 at their discharge ends.

2. In a cooling apparatus, chambers remote from each other, and tubes connecting said chambers, said tubes being of greater length than width in cross-section and having those sides which are in closest relation to each other throughout the main portion of the tube closer together at their discharge ends than at any other portions of the respective tubes. 100 105

3. In a cooling apparatus, a plurality of chambers having transverse funnel-shaped air-tubes passing therethrough, a plurality of tubes connecting the chambers with each other, said tubes being long and narrow in 110 cross-section.

4. A cooling apparatus having a plurality of cooling-tubes which are long and narrow in cross-section and are still further restricted at their discharge ends by a closer approach 115 of those walls which are the nearest to each other throughout the bodies of the tubes.

5. A cooling apparatus having a plurality of cooling-tubes which are long and narrow in cross-section the walls of which at the 120 sides of the tube, are brought still closer together at their discharge end.

6. In a water-cooler, a hollow base divided by partitions into compartments, a hollow cap also divided by partitions into compartments, a water-supply pipe discharging into one of the compartments of the cap, and a water-discharge pipe taking water from one of the base compartments, and a plurality of vertical tubes in a plurality of rows for each 125 130 135

compartment, staggered with relation to each other in the several rows, said tubes forming conduits between the cap and base compartments, said tubes being flattened on opposite sides to form conduits of greater length than width in cross-section.

7. In a water-cooler, a body portion open at front and rear and containing a plurality of cooling-tubes arranged in staggered rows, each of said tubes being long and narrow in cross-section, a hollow cap removably secured upon said body portion with the interior of which said cooling-tubes communicate, slotted dowel-pins entering the body from the cap, keys passing through the slots of the dowel-pins to lock the cap to the body and a hollow base upon which said body portion is removably secured, and with the interior of which base said cooling-tubes communicate, and a supply-pipe to and a discharge-pipe from said apparatus.

8. In a water-cooler, a body portion open at front and rear and containing a plurality

of cooling-tubes arranged in staggered rows, each of said tubes being long and narrow in cross-section and narrower at their discharge ends than at any other portions of the tubes, a hollow cap removably secured upon said body portion with the interior of which said cooling-tubes communicate, and a hollow base upon which said body portion is removably secured, and with the interior of which base said cooling-tubes communicate, said cap and base having air-tubes passing transversely therethrough, a supply-pipe for water discharging into said cap, and a pipe discharging from said base.

In witness whereof we have hereunto set our hands and seals, at Indianapolis, Indiana, this 28th day of November, A. D. 1904.
